(57) **CLAIM**

The ornamental design for a vehicle decklid, as shown and described.

DESCRIPTION

FIG. 1 is a perspective view of the vehicle decklid;

FIG. 2 is a front view thereof;

FIG. 3 is a left side view thereof (where the right side view is omitted since the right side view is a mirror image of the left side view); and,

FIG. 4 is a top view thereof.

In the drawings, the portions shown by broken lines form no part of the claimed design.
